ROLLER SKATE

Edward M. Holden, Niagara Falls, Ontario, Canada

Application October 10, 1958, Serial No. 52,925

Term of patent 14 years

(Cl. D34—14)

Fig. 1 is a side view of a roller skate embodying my new design.

Fig. 2 is a plan view.

Fig. 3 is an end view.

Fig. 4 is a second end view.

The reverse side is substantially the same as the one shown except for the plates.

I claim:

The ornamental design for a roller skate, as shown and described.
